UNITED STATES PATENT OFFICE.

JOSEPH R. PAYSON, OF CHICAGO, ILLINOIS.

GAS HOLDER.

Application filed February 14, 1920. Serial No. 358,722.

To all whom it may concern:

Be it known that I, JOSEPH R. PAYSON, a citizen of the United States, residing at Chicago, in the county of Cook and State 5 of Illinois, have invented certain new and useful Improvements in a Gas Holder, of which the following is a specification.

This invention relates to that class of gas holders which is designed for holding or 10 storing high pressure gases in a practically cold state, although, of course, it may be used for holding and generating hot gases such as steam and the like. The principal object of the invention is to provide a gas holder for all sorts of commercial gases which shall be of light weight, but at the same time of great strength for resisting internal pressure. To this end my invention 15 consists in a gas container which is constructed partly of tempered or heat treated alloy steel of high tensile strength. This is accomplished by constructing the container in two practically concentric receptacles, an inner one of weaker material which is gas tight, and an outer one which need not be gas tight, but is very strong. The main reason for this double construction is that steel of high tensile strength which is tempered to obtain this quality renders the steel 20 comparatively brittle, making it almost impossible to rivet plates together in order to render them gas tight or to prevent them from cracking. In fact, any hard blow to such tempering is apt to cause fractures or 25 minute cracks which may cause the container to leak, and if it contains gas, to render an explosion possible.

While a double container is particularly desirable, a somewhat cheaper construction 30 for lower pressure may be produced by dispensing with the inner container. In this case, the plates may be united in any one of the ordinary methods, such as by riveting them together, then welding the plates at as low a temperature as possible, and 35 wherever possible, by brazing them, as this latter method can be accomplished with less heat and without drawing the temper from the plates. If high pressures are employed, 40 the welding may be by the acetylene torch, after which the finished container is heated to the required temperature, plunged in oil or water, and the temper drawn to the desired point by any of the well known heat 45 treatment methods.

In a double container of this kind it is

practically impossible to construct two substantially concentric containers without creating spaces between the walls. This causes the inner or weaker one to expand under the 50 internal pressure in order to fit these cracks or spaces. This is almost certain to crack or to weaken the inner container, and in order to obviate this difficulty, a suitable cement is introduced between the walls to 55 fill or cover the cracks or interstices.

Provision is also made for preventing the containers from rusting or corroding when certain materials are stored therein, and thus 60 destroying the inner container. Safety devices are provided to prevent air from entering and for rendering the holder more 65 practicable. The invention consists in the novel construction, combination and arrangement of the several parts.

In the accompanying drawing, Fig. 1 is a sectional view of a gas holder constructed in accordance with the principles of my invention; Fig. 2 is a sectional view of one end of such a holder; Fig. 3 is an enlarged fragmental detail showing two walls and a filling cement between them; Fig. 4 is a sectional view of a variation of the joint between the plates of the outer container; Fig. 5 is a sectional view of another plate joint 70 modification taken on the line 5-5 of Fig. 8; Fig. 6 is a section taken on the line 6-6 of Fig. 4 showing one of the jointing nuts; Fig. 7 is a sectional view taken on the line 7-7 of Fig. 8; Fig. 8 is a plan view of the joint also shown by Figs. 5 and 7; Fig. 9 is a view similar to Fig. 3, but showing the shell of the outer container made of 75 laminations; Fig. 10 is a view partly in section of my invention applied to a railway 80 tank car; and Fig. 11 is a view partly in section showing the invention applied to a pipe line.

In Fig. 1 an outside shell 2 is formed by 85 plates which are lapped and fastened together by bolts and nuts 7, and an inside container 3 may be substantially seamless or made of plates welded, brazed, or otherwise fastened together, so as to be gas tight. The inner container is intended to fit closely 90 within the outer one, but any interstices or inequalities between the walls thereof are filled with a cement 4 which preferably hardens in place, as indicated more clearly 95 in Fig. 3. In some places there will be little or none of this filling on account of 100 the close fitting of the shells. The cement 105

or filling is made of materials whose coefficient of expansion is practically the same as that of the steel walls of the container, as for example, Portland cement alone or 5 mixed with zinc or other metal filings. It may also consist of sand or other loose material.

A further object of this cement 4 is that it precludes the necessity of making the interior shell of very great thickness as it attaches or binds the two shells together, preventing to a considerable extent the escape of gas from the inner one. Of greater importance than this is the fact that the 10 cement prevents the collapse of the inner receptacle when a partial vacuum is created therein as for example, when air is pumped out of the container when first the latter is to be filled with gas. The cement prevents 15 air pressure entering through the joints of the outer shell 2 and exerting inward atmospheric pressure, and also from becoming detached from the outer shell 2 at any point, thus preserving the spherical form of the 20 inner shell.

In order to compensate for the low expansibility of cement it should be made flexible by a small content of rubber, varnish or the like. In some cases it is also advantageous to have the cement fusible so as to be 30 easily removed by heat should a leak occur in the inner shell, necessitating a removal of the latter for repairs. The inner container may be made of aluminum, brass, 35 hard rubber, or any non-corrosive, but sufficiently durable material. A vulcanized rubber bag may be used if desirable if it is made with cloth fibre incorporated therein, such as is used for garden hose. Where the nozzle pipe enters this bag, instead of a plug of 40 aluminum or metal 14' (Fig. 1), a plug or extra thickness of rubber can be used with possibly a metal plate vulcanized upon the 45 interior of the container. A rubber bag is not as good as metal as the cost is greater, and it has a shorter life. Furthermore, any small opening around the joint of the outside shell may cause the rubber to blow out unless the latter is very thick and strong. 50 Some gases will also cause the rubber to deteriorate, but for other purposes it may answer as well as a metal container.

In the preferred form of my invention an 55 ingress pipe 12 is for supplying any gas to be compressed in the container by any suitable compressing means as represented diagrammatically by a pump cylinder 5, and a plunger 10, which receives the gas from supply pipe 11.

An egress pipe 14 permits gas to escape 60 from the inner receptacle 3 into a chamber 6, and from there through a cock 18 and a pipe 15 to any device such as an engine or a lamp for using the gas. A piston 16 in the 65 chamber 6 opposes the escape of gas by rea-

son of the spring 17, but allows the gas to enter the pipe 15 when the pressure within the inner receptacle does not fall below a predetermined minimum. When the pressure becomes too low, the spring 17 forces the piston 16 to cover the opening for the pipe 15 so that no more gas can escape.

The ends of the outer receptacle each comprise a dished head 8 with a bent edge which is secured to the outer shell 2 by means of 70 bolts 9, as shown more clearly in Fig. 2.

A plug 14' of sufficient size and thickness is usually welded or attached to the inner container 3 to provide sufficient material so that the pipes 12 and 14 may be attached 80 thereto.

Instead of bolting the plates of the outer shell together, as shown in Fig. 1, or in the manner shown by Fig. 2, the ends 24 of the outer shell may be formed with a bend 25, as 85 shown more clearly by Fig. 4, with the extremities 26 bent or upset so that a fastening nut 27 with slots corresponding to these upset ends may be slid over them and positioned close together, as indicated by the 90 dotted outlines in Fig. 6 for the full length of the joint. Both the edges and the locking nuts 27 are preferably tempered to prevent them from bending open under pressure, and it will be obvious that the more pressure 95 that is applied from the inside of the container, the more tightly the edges will be clamped and engaged.

Another form of joint lock is shown in Figs. 5, 7 and 8, in which the extremities 19 100 of two adjacent plates are formed with upset ends 20, having outer undercut projections 23 adapted to be engaged by a slidable locking nut 21 with a corresponding undercut groove to tightly engage the projections 23.

In this construction the locking nuts 21 may be moved up close together as indicated in Fig. 6, or they may be spaced apart as shown in Fig. 8, since the plates abut, and the under cut projections 23 may be omitted at intervals leaving a space 24 for applying and removing the nuts. In this case a strengthening strap 22 is applied over the 110 shells and bolted thereto by nuts and bolts 28.

It will be seen that this invention is readily applicable to a railway tank car, as indicated, for example, in Fig. 10. An outer shell A comprises a plurality of over-lapping plates which are fastened together by bolts 7, and at the ends by suitable fastening bolts 9. An inner shell or receptacle B is provided, and the spaces between the two shells are filled with a cement filler. A high pressure tank car may be thus constructed with an outer shell of great strength, which as previously explained, need not be absolutely gas or fluid-tight.

This same idea may be utilized in pipe 115

lines as illustrated in Fig. 11, in which the outer pipe sections 29 are bolted together at the flanges 30, and a continuous inner tube 31 has its sections brazed or welded together 5 to make a fluid and gas tight connection. A cement or other suitable material 4 may be introduced between the shells for the purpose previously explained.

While several methods of uniting the abutting edges of the outer container plates have been described, it is obvious that other devices may be used. A laminated shell as shown for example in Fig. 9 may consist of a number of layers 32 of heat treated sheet 10 material wound in circular form upon each other with the inner and outer ends 33 thereof brazed or welded to the adjacent laminations. The edges only of these ends 33 may be provided with a filler 34 such as solder 15 or the like in order to make the container gas tight. The friction of the laminations upon each other, helps to prevent their separation under pressure from within so that the attachment of the ends only is sufficient to hold the laminations together, and the laminations make a shell of great 20 strength and comparatively light weight, particularly if they are of high tensile strength steel. Of course, the head may also 25 be formed of laminated sheets and attached to the shell as shown in Fig. 2.

If desired, either a single or double construction may be used in a boiler for generating steam, especially for steam automobiles where light weight and high pressure are particularly desirable. The cooling effects of the enclosed water would prevent the outer tempered clamps or walls from being so greatly heated as to destroy their 30 temper and their tensile strength.

Although a double gas container is preferable, it is evident that for certain uses the inner container may be dispensed with, for instance, if the joint lock or fastening shown 35 in Figs. 4 and 5 is brazed or welded at the points 24' before the container is tempered or heat treated, it will be gas tight when it is later tempered to the proper degree, or the laps may be welded at 7' as shown in 40 Fig. 1, and the nuts or rivets 7 may be welded and the whole container tempered. This construction is not considered as good 45 as the double construction, but for reduced pressures it may answer very well and limit the construction expense.

The invention is, therefore, considered to include a tempered clamp or shell that completely or substantially covers a container, and especially when the outer container is 50 made of special or alloy steel. It is more properly described as a separate non-gas tight, extremely high tensile strength guard boiler, superimposed upon a weak non-pressure resisting container which in reality is 55 an interior gas tight envelope. This distin-

guishes the invention from being called simply a double boiler in the common interpretation of the term; nor is the outer container simply a pressure resisting clamp. It is of different heat treated or tempered alloy steel 70 completely covering or containing the interior receptacle. Containers of this kind can be made with one fourth or one sixth of the metal now used for high pressure containers and with the consequent freedom 75 from leakage or repairs, it will be found advantageous to store many gases under high pressure, especially oil and coal gases which do not separate too much or condense under high pressure, when they are to be 80 used for lighting purposes, for household use, for cooking, and the like.

Containers of this kind are intended for relatively high pressures, 2000 pounds or more, and if the ordinary container were 85 used, with the normal factor of safety the thickness of the metal required would make the weight prohibitive. By having the outer shell of tempered heat treated steel of high tensile strength, the holder is safe and 90 strong, and is light enough to be easily handled.

I claim:

1. A holder for fluid under pressure, comprising a fluid tight inner receptacle, and an outer receptacle having a wall composed of layers of tempered steel.

2. A holder for gas under pressure, comprising two substantially concentric shells, the inner one of which is gas tight and expansible under pressure but incapable of alone withstanding the gas pressure, and the outer one fitting closely over the inner one and being formed of comparatively non-expansible tempered steel with joints that 105 are not gas tight.

3. A holder for gas under pressure, comprising an inner container of relatively weaker material which is gas tight, in combination with a close fitting and non-yielding outer receptacle, having a heat treated shell comprising plates which are connected with welded joints.

4. In a holder for gas under pressure, an inner container expansible and contractable under pressure, an outer container which fits closely over the inner one relatively unyielding under pressure, and a cement which fills the space between the receptacles and attaches the outer wall of the inner one to the inner wall of the outer receptacle to prevent the inner one from collapsing when a partial vacuum is made therein.

5. In a holder for gas under pressure, an outer receptacle comprising plates of high tensile strength overlapping and connected together, but not necessarily gas tight, in combination with a gas tight expansible receptacle which fits closely within the outer receptacle, means for introducing a gas un-

der pressure within the inner container, and an outlet therefor comprising a valve which prevents the outflow of gas under pressure from the inner container when the pressure thereof reaches a predetermined minimum.

6. In a holder for gas under pressure, an outer receptacle which need not be gas tight but is substantially inflexible under pressure, a yielding inner gas tight receptacle 10 adapted to fit closely within the outer one, separate means for admitting and discharging fluid under pressure to and from the inner receptacle, and a thickening block of material attached to a portion of the interior 15 wall of the entire receptacle so that the said means for admitting and discharging fluid under pressure may be attached thereto.

7. In a holder for gas under pressure, the combination with an outer receptacle formed 20 of overlapping heat treated laminæ secured

together and not necessarily making a fluid tight joint, but substantially inflexible under pressure, of an inner fluid tight receptacle composed of material adapted to expand under pressure, and tending to fill all 25 the cracks and crevices in the interior of the outer receptacle, and means applied to the interior of the outer receptacle and filling the spaces between the two receptacles so that the inner one will not be weakened or blown 30 out under pressure by the interstices and inequalities of the outer receptacle.

8. A gas holder comprising an outer receptacle formed of laminations of treated 35 steel of high tensile strength, the inner and outer edges of the laminations being attached to the adjacent laminations, and a gas tight but relatively weaker receptacle fitting closely within the outer one.

JOSEPH R. PAYSON.
